(57) **CLAIM**

We claim the ornamental design for a light assembly, as shown and described.

DESCRIPTION

FIG. 1 a back, right perspective view of a light assembly having bendable necks of the new design, including a base portion, two bendable neck portions projecting therefrom, and two light heads at distal ends of the two neck portions. FIG. 2 is a back perspective of the light assembly of FIG. 1. FIG. 3 is a front perspective view of the light assembly of FIG. 1.

FIG. 4 is a left elevational view of the light assembly of FIG. 1.

FIG. 5 is a top view of the light assembly of FIG. 1; and, FIG. 6 is bottom view of the light assembly of FIG. 1. The broken line disclosure represents portions of the assembly which forms no part of the claimed design.
